UNITED STATES PATENT OFFICE

PAUL NORTH, OF LAKWOOD, OHIO, ASSIGNOR TO THE CHAMBERLAIN CARTRIDGE & TARGET COMPANY, OF CLEVELAND, OHIO, A CORPORATION OF OHIO

TARGET TRAP

Application filed January 10, 1931. Serial No. 507,841.

This invention relates to target traps, and more particularly to the "shovel" type of throwing arms or carriers for such traps.

As is well known to those skilled in the art to which this invention relates, the ordinary shovel type of throwing arm or carrier is pivoted at one end and is provided with a base for the reception of the targets, being provided at one side with a flange along which one or two targets roll under the influence of centrifugal action, as the carrier is rotated, leaving the carrier at the end of such flange which is most remote from the pivot.

Carriers of this type have been constructed heretofore of aluminum, for the purpose of securing the necessary lightness in weight to prevent destructive racking of the traps by intercepting or stopping the movement of such carriers at the ends of their throwing strokes or operations; also for the purpose of enabling the carriers to be effectively intercepted and stopped at the ends of their respective throwing movements.

As bases of the shovel carriers have been constructed heretofore, the width of the bases of the same has been equal to the diameters of the targets thrown thereby; and, in order to secure the desired degree of lightness, a considerable proportion of the metal of each such base has been removed by perforating the base.

It has been found that the employment of shovel carriers of the construction described has resulted in the breakage of a considerable proportion of the targets thrown thereby. This breakage is due in part to the fact that the surface of the base along which the targets roll is sufficiently rough to impart a wobbling, fluttering or vibratory motion to the targets moving therealong, which will cause a considerable proportion of the targets to break while traveling at high speed. This wobbling, fluttering, or vibratory motion is increased by the openings which have been provided for the purpose of lightening the weight of the carriers, due to the passage of air through these openings while the targets are traversing the carriers.

It is the general purpose and object of this

invention to provide for target traps of the character referred to a throwing arm or carrier of the shovel type which will possess the requisite degree of lightness to avoid racking the machine and to permit stopping the carrier at the desired point in its travel, while reducing to a minimum the breakage of targets due to the causes explained hereinbefore. I accomplish the foregoing general objects in and through the construction and arrangement of parts shown in the drawings hereof, wherein Fig. 1 represents a side elevation of a target trap having a carrier or throwing arm applied thereto and embodying my invention; Fig. 2 a plan view, and Fig. 3 a side elevation, of the said carrier or throwing arm; Fig. 4 a bottom plan view of the carrier or throwing arm; and Fig. 5 a detail in section corresponding to the line 5-5 of Fig. 2.

Describing by reference characters the various parts illustrated herein, 1 denotes a base and 2 the frame of a target trap, which trap may be of the type shown, described, and claimed in the patent to Spangler No. 1,771,865, issued July 29, 1930 and comprising generally a throwing shaft 3 having at its upper end a crank 4 to which the carrier, indicated generally at 5, is connected, as by a bolt 6. The lower end of the shaft is connected by intermediate connections 7 and 8 with a rod 9 connected to the throwing spring 10, the opposite end of the said spring being connected by a rod 11 with an arm 12 which is pivoted at 13 and connected at its opposite end with the pull rod 14. 15 denotes a sliding rod which is connected at one end to the lever 16 which is adapted to engage a stud 4^a depending from the crank arm 4 and normally hold the carrier 5 in the throwing position shown in Fig. 1. The lever is held in stud-engaging position by means of the spring 17 surrounding the stem and bearing at one end against the stop 18 and at its other end against the collar 19 on the said rod, the movement of the lever from stud-engaging position being normally prevented by the engagement of the rod 15 with the arm 12. The parts 1 to 4 inclusive and 6 to 19 inclusive may be of the construction shown and described more par-

ticularly in the Spangler patents and, in their details, form no part of the invention intended to be protected hereby.

The carrier is provided at one end with a reduced extension 20 having an aperture 21 therethrough by which the carrier is pivotally mounted on top of the shaft 3 and is also provided with an opening 22 for the reception of the bolt 6 by which it is secured to the crank arm 4. The carrier is of the general shape of the shovel carriers referred to hereinbefore, but consists in general of a two-part base comprising a thin upper ply or sheet 23 of steel and a lower plate 24 of aluminum. In practice, I have employed for the upper ply or member of the base steel having a thickness of .018 inch. For the lower member of the base, I employ an aluminum plate of substantially the same outline as the steel plate (but somewhat wider, as will appear more particularly from Fig. 2) the aluminum base portion being the part that is provided with the extension 20 and also having adjacent to the pivotally supported end thereof a short upwardly projecting rib 25 located rearwardly of the rear edge of the upper ply or member and shown as provided with integral short posts 26 which support the flange (indicated generally at 27) along which the targets roll as the carrier is rotated. The rib 25 preferably does not extend the full length of the aluminum base member, and additional posts 26^a project from the rear edge of the said member and cooperate with the posts 26 in supporting the flange.

In order to obtain the necessary lightness in the complete arm, I have found that I can make the base of the carrier approximately two-thirds the width of the all-aluminum bases heretofore employed and, because of the smoothness and freedom from access of air to and below the targets (due to the continuous smooth surface of the upper steel member of the base) I am able to throw the targets efficiently and, in addition, to accomplish this result without breakage due to wobbling, fluttering, or vibratory movements thereof during their travel. As a further means for securing the lightening of the carrier, I have reduced the thickness of the central portion of the aluminum base member by recessing the same upwardly, as shown at 28; I have also reduced the weight further by removing a large proportion of the aluminum member intermediate the thickened reinforcing edge portions 28^a, 28^b thereof, as indicated by the openings 29, 29^a. The upper and lower base members are conveniently united by rivets 30, the upper heads of which are flush with the upper face of the sheet steel member 23.

The flange 27 referred to hereinbefore may be of standard construction and comprises generally a channel-shaped metal member carrying a rubber 31, similar to a squeegee,

the flange being secured to the posts 26 and 26^a by screws 32.

Due to the manner of constructing the carrier, I am enabled to obtain a carrier which obviates the breakage due to the wobbling, fluttering, or vibration of the targets as they travel along the carrier in contact with the rubber member 31 of the flange and I am enabled to obtain this result with the employment of a carrier which is approximately as light as the former all-aluminum carriers. The steel upper member or plate 23 strengthens the aluminum (which has been lightened in the manner described hereinbefore) so that the base will stand up, notwithstanding such lightening; and at the same time this steel plate provides a far smoother surface for the targets to travel along than is obtainable by the use of aluminum, thereby reducing the liability of the targets to wobble, flutter or vibrate while traversing the same. Furthermore, as pointed out hereinbefore, a carrier arm constructed in accordance with my invention is relatively inexpensive of production.

Having thus described my invention, what I claim is:

1. A carrier for a target trap comprising a base having a bottom supporting member of relatively light metal and an upper member secured to the former member, the latter member being of relatively strong thin sheet metal having a smooth upper surface adapted to be traversed by the targets under the influence of centrifugal force.

2. A carrier for a target trap comprising a base having a bottom supporting member of relatively light material and an upper target engaging member supported by the former member, the latter member being a relatively strong, thin sheet having a smooth upper surface adapted to be traversed by the targets under the influence of centrifugal action.

3. A carrier for a target trap comprising a bottom supporting member of relatively light metal and having secured to the upper surface thereof an upper member comprising a thin sheet of relatively strong and heavier metal, the said sheet having a smooth upper surface along which the targets may travel by centrifugal action, the lower member having its lower surface recessed or depressed upwardly within the edges thereof and having an upper surface adapted to be engaged by the bottom of the upper member.

4. A carrier for a target trap comprising a lower supporting member made of relatively light metal and having secured to the upper surface thereof an upper member comprising a thin sheet of relatively strong and heavier metal, the said sheet having a smooth upper surface along which the targets may travel by centrifugal action, the lower member having its lower surface recessed or de-

pressed upwardly between the edges thereof and having such upwardly depressed portion provided with apertures therethrough, said lower member providing an upper plane surface adapted to engage and support the lower surface of the upper member and having vertically thickened edges.

5. A carrier for a target trap comprising a bottom supporting member of relatively light metal and having secured to the upper surface thereof an upper member comprising a thin sheet of relatively strong and heavier metal, the said sheet having a smooth upper surface along which the targets may travel by centrifugal action, the lower member having posts projecting upwardly from the rear edge thereof, and a flange secured to said posts and arranged to engage the peripheral portions of the targets which travel 10 along the upper surface of the upper sheet.

20 In testimony whereof, I hereunto affix my signature.

PAUL NORTH.
